UNITED STATES PATENT OFFICE.

JOHN LAWLESS, OF SPRINGFIELD, ILLINOIS, ASSIGNOR OF ONE-HALF TO JOHN McGARITY, OF SPRINGFIELD, ILLINOIS.

CAR-CAGER.

1,044,460.

Specification of Letters Patent. Patented Nov. 12, 1912.

Application filed March 1, 1912. Serial No. 680,903.

To all whom it may concern:

Be it known that I, JOHN LAWLESS, a citizen of the United States, residing at Springfield, in the county of Sangamon and State 5 of Illinois, have invented a new and useful Car-Cager, of which the following is a specification.

This invention relates to means for placing loaded mine cars on the cage of a mine, 10 or removing the empty cars from the cage without the necessity for the attendant to go on or under the cage.

The purposes of the invention are: to provide means to keep the car on the cage during the ascent or descent of the cage; to provide an automatic releasing device actuated by the descending cage and adapted to automatically release the empty car when the cage is on the level of the loading and discharging tracks; to provide means for keeping a plurality of cars on the loading track in position for caging, and means for releasing the first loaded car, so that it may run onto the cage, but holding the next succeeding car so that not more than one car 25 at a time can run onto the cage; to provide a starter energized by the descending cage and adapted to automatically push and start the loaded car to run onto the cage; to provide means whereby a car placed on the cage may be released in case it be desired to remove the car from the cage and run it back on the loading track; to provide means for placing the caging mechanism out of 30 commission to admit of operating the cage without operating the caging mechanism; and to provide other novel features of construction hereinafter set forth.

The invention is illustrated in the annexed drawings to which reference is hereby made and is hereinafter described and the novel features recited in the claims.

Figure 1 is a top plan of the mechanism; and Fig. 2 is a side elevation of the mechanism.

Similar reference characters designate like parts in both views.

The cage 1 is of the usual construction and is connected with the hoisting cable 50 so that the cage will travel upwardly and downwardly in the shaft, guided by the guides 2. On the floor of the cage is a track 3 which supports the car on the cage.

When the cage is at the bottom of the pit the track occupies a position in the plane 55 of the loading track 4 and the discharge track 5. Pit cars 6 of usual construction are adapted to travel on the tracks.

Extending downwardly from the center of each car is a fixed stop 6^a. The purpose 60 of which is hereinafter explained.

A shaft 7 transverse to the loading track is mounted to oscillate on suitable supports 7^a. A beam 8 is secured on the shaft 7 and a weight 9 is mounted near one end of the 65 beam. One end of the beam 8 is adjacent to one wall of the shaft in which the cage travels. A projecting finger 10 secured on the cage engages one end of the beam 8 and as the cage descends the finger depresses the 70 engaged end of the beam and causes the shaft 7 to oscillate and raise the weighted end of the beam. A transverse bar 12 secured on the beam 8 supports upwardly extending slotted standards 13. Shafts 14 fit 75 loosely in the slots of the standards 13 and are supported on the standards. Weights 15 are secured on the shafts 14 respectively. Circular blocks 16 are mounted to slide on the shafts 14 respectively. Cylinders 17 are 80 secured on the blocks 16 and when the loaded car is in position for starting the outer ends of the cylinders 17 abut against the stop 6^a on the under side of the car. Helical springs 18 surround the shafts 14 85 respectively. One end of each spring is connected with the block 16 and the other end abuts against the standards 13.

During the depressing of the free end of the beam 8 by the finger 10 on the cage, the 90 depressing of the beam will cause the upper part of the standards 13 to act on the ends of the springs 18 to compress the springs.

Previously to the depressing of the beam 8 the upper ends of the cylinders 17 will 95 be in contact with the stop 6^a on the under side of the loaded car at rest on the loading track; hence the moving of the standards 13 will cause compression of the springs 18 and the energy of the springs will be stored and 100 utilized to start the car when the stop which holds the car is released.

The practical advantage of the described construction is that the stored energy of the springs is effective to overcome the inertia 105 of the car and start the car.

Upon occasion it may be desired for the loaded car to pass over the cylinders 17 without the cylinders engaging on the stop 6^a. In that case the cylinders will be depressed by means now to be described.

A bent shaft 19 is mounted to oscillate in suitable bearings 20. The shaft 19 has upwardly extending members 19^a and a horizontal member 19^b. Forks 19^c in the member 19^b accommodate the shafts 14 respectively. If the shaft 19 be oscillated to the right to move the member 19^b upwardly the forks 19^c will engage on the underside of the shafts 14 and raise the shafts to the horizontal position indicated by dotted lines. When the shafts 14 and the cylinders 17 are in the horizontal position, the stop 6^a will pass over them without striking the cylinders.

Horizontal bell-crank levers 21 and 22 are mounted to oscillate on suitable supports. A rod 23 connects the bell-crank levers 21 and 22. A lever 24 mounted on a standard 25 is connected with the bell-crank lever 21 by a rod 26.

A rod 27 mounted to slide in suitable supports 28 is connected with the bell-crank lever 22 and one end of the rod is turned upwardly and has a pivot 27^a connecting the rod with one member 19^a of the lifter. The other end of the rod 27 is bent upwardly and has a laterally extending finger 27^b adapted to engage with an upwardly extending arm 29 on the transverse shaft 30. The shaft 30 oscillates in suitable supports 31. Arms 29 and 32 and a lever 71 are secured on the shaft 30. The arm 29 is adapted to be engaged by the finger 27^b on the rod 27. The arm 32 extends upwardly in position to be engaged by the stop 6^a on the underside of the loaded car running onto the cage. The lever 71 tends to gravitate to restore the parts to their initial positions after the arm 32 has been depressed by the stop 6^a of the car moving over it. A wire 33 connects the lever 71 with the clapper of a suitably placed signal bell 34, so that when the arm 32 is turned downwardly the bell will be caused to ring.

When the front wheels of a loaded car are traveling to the right on the cage the stop 6^a on the underside of that car will strike the upwardly extending end of the arm 32 to depress it to cause the lever 71 to pull on the wire 33 to cause the bell 34 to ring to apprise the engineman that the car is in place on the cage in readiness for hoisting.

If it be desired that a car moving to the left pass over the cylinders 17 without being engaged thereby, the upper end of the lever 24 will be moved to the left and will cause the rod 26 to push on the bell-crank lever 21 and through the instrumentality of the rod 23 cause the bell-crank lever 22 to act on the rod 27 and the rod 27 pulling on the

member 19^a will raise the lifter and cause the cylinders 17 to assume a horizontal position (shown in dotted lines in Fig. 2) so that the stop 6^a will pass over the cylinders without striking them.

In order that the springs 18 may be compressed, it is necessary to hold the car to prevent it from moving forwardly while the springs are being compressed.

The holder will now be described. A bar 35 equipped with a weight 35^a is mounted to oscillate on standards 36. A beam 37 in line with the bar 35 is mounted to oscillate on standards 38 and has a hinged member 37^a extending under the bar 35 and having an opening adapted to permit free movement of the weight 35^a. A finger 39 connected with the cage engages one end of the beam 37 just before the track on the cage arrives in the plane of the loading track and depresses that end of the beam which is engaged by the finger and causes the other end of the beam to raise the weighted end of the bar 35 to the horizontal position shown in Fig. 2 and when the bar 35 is in that position, the other end of the bar will be disengaged from the stop 6^a and the car will be free to run over the bar 35 and downward on the loading track and onto the cage. A shaft 40 oscillates in supports 41. An inclined latch 42 having a shoulder 42^a is fixed on the shaft 40. A pin 43 extends laterally from the bar 35 and normally acts when the weighted end of the bar is depressed, to keep the latch in the position shown by dotted lines in Fig. 2.

A weight 44 secured on the shaft 40 tends to gravitate to turn the shaft to move the upper end of the latch to the left. When the member 37^a is raised it will raise the weighted end of the bar 35 so that when the bar is in a horizontal position the weight 44 will gravitate and cause the shoulder 42^a to occupy a position under the pin 43 and thereby support the bar in its horizontal position. As the car on the loading track moves toward the cage the front end of the car will strike the upper end of the latch 42 and restore it to its initial position (shown in dotted lines in Fig. 2) and thereupon the weight 35^a will gravitate to cause the bar 35 to assume its initial position in readiness to stop that car.

A horizontal shaft 45 is mounted to oscillate in stationary standards 46 and has a handle 45^a. A horizontal arm 47 is secured on the shaft 45 and when the shaft is turned upwardly to the left the arm 47 engaging on the underside of the beam 37 will raise the beam and support it in the position indicated by dotted lines in Fig. 2. A bent rod 48 is secured on and extends downwardly from the beam 37. A chain 49 connects the rod 48 with the latch 42 so that when the beam is raised the chain 49 will

pull on the latch 42 and hold it in such position that it can not engage with the pin 43. When the beam 37 is raised the outer end of the beam will be out of the path 5 of the finger 39 on the cage so that the cage may move upwardly or downwardly without the finger engaging on the beam. When the beam is raised as described the weighted 10 end of the bar 35 will be depressed and the other end of the bar will be in position to stop and hold the first car running on the loading track.

The keeper on the cage will now be described. Levers 50, 51, 52, and 53 are mounted to oscillate in fixed vertical standards 54, 15 55, 56, and 57 respectively. The lever 51 has a slot 51^a accommodating a pin 52^a on the lever 52. A spring 58 connects the lower 20 ends of the levers 50 and 51. Stationary pins 59 limit the inward movement of the lower members of the levers 50 and 51 respectively, and stop them in such position that the upper ends of the levers will be respectively adjacent to the sides of the stop 6^a on the 25 underside of the car. One member of the lever 53 engages on the lever 52 and the other member of the lever 53 engages on a latch 60 suitably supported on the wall of the shaft. When the cage descends one end 30 of the lever 53 engages on the latch 60 and is thereby raised, and the other end of the lever 53 acts to depress the contacting member of the lever 52 and the lever 52 in turn acts to raise the lower member of the lever 35 51 so that the upper end of the lever 51 will be below the stop 6^a and the car will be free to run off the cage and onto the empty track.

The latch 60 oscillates on a suitable support 40 61 stationary on the frame work of the shaft. An arm 62 is connected with the latch 60. A chain 63 connected with the arm 62 extends around a sheave 64 suitably supported on the frame work of the shaft 45 and supports a weight 65. An angular lever 66 is mounted on a shaft 67 which oscillates in suitable supports on the frame work of the shaft. A chain 69 connected with the upwardly extending member of the lever 66 50 runs around a suitably supported sheave 68 and is connected with the rod 70. The rod 70 connects the chain 69 with the lever 45^a so that when the upper end of the lever is moved to the left the beam 37 will be raised 55 as already described to clear the finger 39 and the lever 66 acting on the arm 62 will retract the latch 60 as shown by dotted lines in Fig. 2 so that the cage will be free to travel upward or downward without operating the mechanisms of the car-cager. The operation is as follows: If the cage is started 60 from the top with an empty car on the cage the lever 53 will at the proper time engage on the latch 60 to cause the release of the 65 car then on the cage and the empty car will

run off the cage onto the empty track. The descent of the cage will cause the finger 10 to depress the beam 8 to cause compression of the springs 18 as already described and when the track on the cage arrives in the 75 plane of the loading track and the empty track, the finger 39 will actuate the beam 37 to cause the depressing of the left-hand-end of the bar 35 thereby releasing the first car on the loading track and the springs 18 will 75 immediately act to start the car and cause it to run onto the cage. When the car runs onto the cage the stop 6^a on the underside of the car will pass over the lever 50 and stop against the upper end of the lever 51. The 80 spring 58 will cause the lever 50 to return to its first position as soon as the stop 6^a has passed over and the car will come to rest with the stop 6^a between the upper ends of the levers 60 and 51, which will keep the car 85 safely in place on the cage.

If it be desired to run a car from the cage back onto the loading track the upper end of the lever 71 will be moved to the right to depress the arm 32 so that the stop 6^a on the car running from the cage will travel over the arm 32 without striking it and the upper end of the lever 45^a will be moved to the left to cause the bent arm 47 to raise the right-hand member of the beam 37 and cause the rod 48 to pull on the chain 49 and thereby cause the depressing of the upper end of the finger 42 so that the stop 6^a on the car running from the cage may pass over the finger without striking it. The 90 upper end of the lever 24 will then be moved to the left to cause the rod 27 to pull on the lifter 19^a and raise the lifter to cause the cylinders 17 to assume a horizontal position below the plane of the lower surface of the 95 stop 6^a so that the car on the loading track in front of the car running from the cage may be pushed to the left on the loading track and may pass over the cylinders 17 without striking them. When the stop 6^a on the underside of the car running from the cage has passed the upper end of the finger 42, the upper end of the lever 45^a will be 100 moved to the right to cause the release of the beam 37 and permit the finger 42 to 105 assume its normal position, and the upper end of the lever 24 will be moved to the right to cause the rod 27 to slide to the left and depress the lifter 19^a so that the weights 110 15 will gravitate downward and cause the cylinders 17 to assume their raised position and stop the car running from the cage. After the stop 6^a of the car running from the cage has passed over the arm 32, and the finger 42, the lever 71 will gravitate downward to restore the arm 32 and the finger 42 to their initial position and to cause the arm 29 to push on the member 27^b of the 115 rod 27 to cause the lifter 19^a to return to its 120 first or depressed position, and thereupon 125 130

the weights 15 will act to raise the cylinders 17 into position to stop the car coming from the cage.

Having fully described my invention what 5 I claim as new and desire to secure by Letters Patent is:

1. In a car-cager, the combination of a holder adapted to hold a car at rest; a 10 starter provided with springs; spring-compressing means adapted to be operated by the descending cage to cause the starter to exert pressure against the car to start the car; and releasing-means adapted to be operated by the descending cage to disengage the holder.

2. In a car-cager, the combination of a holder adapted to hold the car at rest; a 20 starter provided with springs; spring-compressing means adapted to be operated by the descending cage to cause the starter to exert pressure against the car to start the car; releasing-means adapted to be operated by the descending cage to disengage the holder; and a keeper on the cage adapted 25 to keep in place on the cage the car started by said starter.

3. In a car-cager, the combination of a holder adapted to hold a car at rest; a 30 starter provided with springs; spring-compressing means adapted to be operated by the descending cage; releasing-means adapted to be operated by the descending cage to

disengage the holder; a keeper adapted to stop and keep in place on the cage the car started by said starter; and means for operating the keeper to release the car.

4. In a car-cager, the combination of a car holder; a standard positioned to support a car starter coöperating with the car-holder; a car-starter mounted to oscillate on 40 said standard and provided with a weight normally gravitating downward to raise the forward end of the starter; and means for raising the weighted rear part of the starter to depress the forward end of the starter to 45 permit the car to move rearwardly over it.

5. In a car-cager, the combination of a holder adapted to hold a car to prevent untimely running of the car onto the cage; 50 holder-releasing means adapted to be actuated by the descending cage to disengage the holder; a keeper effective to stop and keep a car running from the holder onto the cage; means for disengaging the keeper; and means connecting the holder-releasing means 55 with the means for disengaging the keeper.

In witness whereof, I have hereunto signed my name at Springfield, Illinois, this 24 day of February, 1912.

JOHN LAWLESS.
